UNITED STATES PATENT OFFICE.

WALTER R. DENMAN, OF AKRON, OHIO.

DESIGN FOR A TIRE-TREAD.

49,953.

Specification for Design.

Patented Nov. 28, 1916.

Application filed September 28, 1916. Serial No. 122,768. Term of patent 14 years.

To all whom it may concern:

Be it known that I, WALTER R. DENMAN, a citizen of the United States, residing at Akron, Ohio, have invented a new, original, and ornamental Design for a Tire-Tread, of which the following is a specification, reference being had to the accompanying drawing, forming part thereof.

Figure 1 is a perspective view of a tire tread showing my new design. Fig. 2 is a plan view of a portion of the same.

I claim:

The ornamental design for a tire tread as shown.

In testimony whereof, I affix my signature.

WALTER R. DENMAN.

Witnesses:

C. A. WOLF,
C. E. ROBERTS.
